ATTORNEY

UNITED STATES PATENT OFFICE.

WILLIAM W. HAYDEN, OF NEWARK, NEW JERSEY.

DESIGN FOR A MATCH-BOX.

SPECIFICATION forming part of Design No. 21,639, dated June 21, 1892.

Application filed May 13, 1892. Serial No. 432,932. Term of patent 3½ years.

To all whom it may concern:

Be it known that I, WILLIAM W. HAYDEN, a citizen of the United States, and a resident of Newark, in the county of Essex and State 5 of New Jersey, have invented and produced a certain new and original Design for Match-Boxes, of which the following is a specification.

The accompanying drawing, which forms 10 a part of this specification, clearly illustrates my newly-designed match-box or receptacle for small articles.

My new design relates to the form and ornamentation of the body and cover, and the 15 leading feature consists of the representation of a palette at the center of the body, surrounded by a branch or wreath of leaves and flowers.

In the drawing, A represents the body, and 20 B the top or cover, of the box. In general outline those approximate a parallelogram,

and three of the corners appear overturned, forming tapering rolls *a b c*, terminating in volutes *a' b' c'* in imitation of a parchment-scroll, at the center of which appears the 25 palette C. The edges of the body show curves *d e* and indentations *d' e'*. The palette is surrounded by a branch *f* of leaves and flowers, and in the orifice of the palette appear artists' brushes and rest *k*. The top or cover 30 shows double curves *g h* at its edges, and its surface is ornamented with a branch *i* of leaves and flowers and also with foliated scroll-work *j*, as shown.

I claim—

The design for a match box, substantially as 35 shown and described.

WILLIAM W. HAYDEN.
